RADIO CABINET

Jack De Young, Grand Haven, Mich., assignor to
Zenith Radio Corporation, a corporation of
Illinois

Application June 19, 1948, Serial No. 147,083

Term of patent 7 years

(Cl. D56—4)

To all whom it may concern:

Be it known that I, Jack De Young, a citizen of the United States, residing at Grand Haven, in the county of Ottawa and State of Michigan, have invented a new, original, and ornamental Design for a Radio Cabinet, of which the following is a specification, reference being made to the accompanying drawing, forming a part thereof.

The figure is a perspective view of the front and side of a radio cabinet showing my new design.

The other side is the same as the side shown and the rear is plain.

I claim:

The ornamental design for a radio cabinet, substantially as shown and described.

JACK DE YOUNG.
